UNITED STATES PATENT OFFICE.

VAN E. SANFORD, OF ST. ALBANS, WEST VIRGINIA.

VALVE.

1,179,225.

Specification of Letters Patent. Patented Apr. 11, 1916.

Application filed March 6, 1915. Serial No. 12,655.

To all whom it may concern:

Be it known that I, VAN E. SANFORD, a citizen of the United States, residing at St. Albans, in the county of Kanawha and State of West Virginia, have invented new and useful Improvements in Valves, of which the following is a specification.

This invention relates to valves and more particularly to automatic cut off valves for gas mains.

The principal object of the invention is the provision of an automatically operated valve which is simple, cheaply constructed and reliable and which will automatically cut off the gas upon a reduction of pressure in the mains so as to prevent explosions in residences and asphyxiation of the occupants resulting from a reduction of pressure in the mains which causes extinguishment of the flame at the lights or burners and the reestablishment of the pressures.

Further objects of the invention will appear as the following description is read in connection with the accompanying drawing, which forms a part of this application, and in which:—

Figure 1 is a longitudinal sectional view showing the position of the valve when the supply is cut off to the house mains and in dotted lines the position when the supply is open to the house mains. Fig. 2 is a perspective view of the valve holding plug. Fig. 3 is a similar view of the valve removed from the plug.

In the specific embodiment of the invention as illustrated herein, I have shown the valve casing 1 of the improved device connected to the service and house main pipes 2 and 3, respectively, by suitable reducing units 4. The casing 1, as shown, is exteriorly threaded at opposite ends to receive the unions or to otherwise connect the same with the supply and house main pipes and has one end closed by a wall 5 having an eccentrically positioned port 6. The opposite end of the casing is internally threaded and screwed therein is a plug 7 having an eccentrically positioned port 8 which when in position in the casing is oppositely disposed to the port 6. The inner end wall of the plug is machined on an angle to produce a valve seat 9 against which the gravi-

tating flap valve 10 is adapted to rest and cover the port or inner end of the channel 8, as will be readily understood. Immediately above the seat 9 the plug is provided with a transverse rib 11 longitudinally slotted as shown at 12 to receive the pivoting shank or ear 13 formed on the valve 10. This ear is pivotally connected to the rib 11 by a pin 14 and has a cam-shaped inner end disposed within a vertical socket 15 arranged to be entered by the set screw 16 or any other suitable type of plunger carried by and passing through the casing 1.

In the adoption of any specific type of plunger its inner end will be located within the recess or socket 15 so as to hold the plug against accidental movement.

It will be noticed that if the valve is in raised position as shown in dotted lines in Fig. 1 that it is in direct line with the flowing fluid passing through the port 6 and as long as the fluid continues to flow it will be maintained in open position. When the pressure is materially reduced or cut off the valve will gravitate to closed position, as shown, and upon a reestablishment of the pressure in the main no fluid will be allowed to pass the valve until the same is again opened by a depression of the plunger 16.

What is claimed is:—

In a valve, a casing having a closed end provided with an eccentrically positioned port, a plug threadedly mounted in the opposite end of the casing and closing the same, said plug having an eccentrically positioned port arranged out of alinement to the first mentioned port, the inner end of said plug having a vertically arranged opening formed therein, a valve pivotally mounted within said plug and normally acting to close said second mentioned port, and a set screw threaded into the casing and extending into said opening, said screw adapted to open said valve and serving to lock said plug within the casing.

In testimony whereof I affix my signature in presence of two witnesses.

VAN E. SANFORD.
